(57) **CLAIM**

The ornamental design for a dog treat, as shown and described.

DESCRIPTION

FIG. 1 is a front, top and right side perspective view of a dog treat, according to our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The stippled shading and the line shading shown in FIGS. 1-7 represent a contrasting appearance.
